H. C. HANSON

CABINET

Filed May 8, 1925

UNITED STATES PATENT OFFICE.

HERMAN C. HANSON, OF EAGLE ROCK, CALIFORNIA.

CABINET.

Application filed May 8, 1925. Serial No. 23,840.

To all whom it may concern:

Be it known that I, HERMAN C. HANSON, a citizen of the United States, residing at Eagle Rock city, in the county of Los Angeles and State of California, have invented 5 new and useful Improvements in Cabinets, of which the following is a specification.

This invention relates generally to cabinets, more particularly to radio cabinets.

10 An object of this invention is to provide a radio cabinet constructed in such a manner that the panel upon which the radio control mechanism is positioned may be covered by a door or closure member which 15 may be locked, in order to prevent small children or unauthorized persons from tampering with the radio control mechanism.

Another object of the invention is to provide 20 a radio cabinet having a pivoted door or closure member, which when closed will cover the panel carrying the radio control mechanism in order that the cabinet may present a neat appearance.

These objects are attained by the 25 closure herein set forth, by the following description of the accompanying drawings illustrating the practical embodiment of the invention, the novel features hereof being pointed out in the appended claims, in 30 which:

Figure 1 is a perspective view of the radio cabinet as it appears when locked or with the closure member covering the radio controlling mechanism.

35 Fig. 2 is a vertical section taken through the radio cabinet on line 2—2 of Fig. 1.

Fig. 3 is a perspective view of the radio cabinet showing the cabinet as it appears with the radio panel exposed.

40 Fig. 4 is a vertical section taken on line 4—4 of Fig. 3.

Fig. 5 is a transverse section taken on line 5—5 of Fig. 2, looking in the direction indicated by the arrows.

45 Referring by numerals to the accompanying drawings, 10 generally designates a panel formed of the usual fibre insulation and is mounted on a frame 12, secured to the sides 11 of the cabinet generally designated at C. The panel 10 is adapted to receive a condenser dial 13, a rheostat 14, and a switch 15 and any other adjusting or controlling apparatus which may be desired. One end of the frame 12 is secured 50 to a brace 16 which is mounted on a front wall 17, upon which is mounted cushions 18.

A closure member 19, has a pair of brackets 20 secured to each end by suitable fastening means and are pivotally connected to the sides 11 by screws or bolts 21 and are 60 adapted to close the cabinet as shown in Figs. 1 and 2 and may be locked in this position by a lock 22 secured to an upper panel 23, the lock 20 having a bolt 24 adapted to engage a keeper. 65

The brackets 20 have extended portions 26, upon which are mounted eye bolts 27 adapted to receive the ends of retractile coil springs 28 which are also connected to eyes 29 fastened to the bottom 30. 70

As shown in Fig. 1, the door 19 is in closed position and its edge 19^a engages the cushions 18. When it is desired to open the cabinet, it is only necessary to slightly press the upper portion and as the door is pivotally mounted it will be easily rotated on the bolt 21 and is aided by the action of the spring 28. 75

As shown in Figs. 3 and 4, the door is in open position and its edge 19^b engages 80 cushions 31 on stops 32 secured to the sides 11.

From the construction it will be seen that the sides 11, front wall 17, bottom 30 and rear wall 33 form a compartment 34, in 85 which the radio set may be mounted.

The upper portion 35 is adapted to receive a horn 36 of a loud speaker and the front panel 37 is provided with a screen or ornamental frame work 38, through which the 90 sound from the horn may pass.

In order to allow for movement of the brackets 20, elongated recesses 12^a are cut in each side of the frame 12. A rear door 39 is connected to the rear wall 33 by a hinge 95 40 and may be provided with suitable locking means, generally indicated at 41. The underside of the closure member 19 is provided with a knob or handle 19^c to facilitate opening and closing. 100

Various changes may be made without departing from the spirit of the invention as claimed.

What is claimed is:

1. A cabinet comprising in combination a bottom, a back and a front wall, the back wall being much higher than the front wall, an inclined closure member having its lower edge resting on the upper edge of the front wall, a front panel parallel to the back and positioned considerably behind the front wall, a pair of end walls and a top for the 105 110 115

- 2
- cabinet, a pair of brackets pivotally mounted on the inside of the end walls, forming a swivel mounting for the inclined closure member, a radio panel positioned within the cabinet, substantially parallel to the inclined closure member when in closed position, said brackets being pivotally mounted in such position whereby when the inclined closure member is swivelled from a closure position 5 substantially parallel to the radio panel, to a position substantially at right angles to the upper edge thereof, the lower edge of the closure member engages the lower edge of the front panel when in its open position and 10 forms an interior closure for the upper part of the cabinet, a brace secured to the front wall, an inclined board extending from the inner end of the brace to the upper edge of the front wall, the said brace and inclined board forming a support for the lower edge 15 of the radio panel.
2. A cabinet having a bottom, a rear wall, a front wall, the rear wall being much higher than the front wall, an inclined closure member extending backwardly and up- 20 wardly from the top of the front wall, a front panel extending upwardly from the upper edge of the inclined closure member, said panel having open work, a loud speaker horn positioned in the upper part of the 25 cabinet and having its mouth adjacent the open work of the front panel, a radio panel supported within the cabinet having radio controlling instruments mounted thereon, a pair of brackets secured to the back of the 30 closure member, said brackets being pivotally mounted within the cabinet, whereby the closure member may swivel inwardly from a position forming a closure between the front wall and the lower edge of the 35 front panel to a position forming a closure for the upper part of the cabinet from the lower edge of the front panel inwardly, said closure member in its inner position being close to the upper edge of the radio panel 40 and preventing access to the interior of the cabinet behind the said radio panel.
- In testimony whereof I have signed my name to this specification.

HERMAN C. HANSON.
